UNITED STATES PATENT OFFICE.

WILLIAM CAIRNS, OF CLEVELAND, OHIO, ASSIGNOR TO PARISH & BINGHAM COMPANY, OF CLEVELAND, OHIO, A CORPORATION OF WEST VIRGINIA.

DESIGN FOR A RUNNING-BOARD FOR AUTOMOBILES.

42,124.

Specification for Design.

Patented Feb. 6, 1912.

Application filed September 16, 1909. Serial No. 518,123. Term of patent 14 years.

To all whom it may concern:

Be it known that I, WILLIAM CAIRNS, a resident of Cleveland, in the county of Cuyahoga and State of Ohio, have invented a new, original, and ornamental Design for Running-Boards for Automobiles, of which the following is a specification, reference being had to the accompanying drawing, forming part thereof, in which—

Figure 1 is a top plan view of a running

board for automobiles, showing my new design. Fig. 2 is an end view of the same.

I claim—

The ornamental design for a running board for automobiles as shown.

WILLIAM CAIRNS.
